CORPORATION OF COLORADO

ROASTING FURNACE

Application filed July 29, 1925. Serial No. 46,734.

Our invention relates to the roasting of mineral sulfides and has particularly in view a means for balancing the temperatures during the roasting operation. The invention is practised particularly in connection with a process of roasting sulfides, wherein the air, ore and sulfur-containing gases travel concurrently or in the same direction through the furnace as disclosed in our co-pending application Serial No. 340,888 (now Patent No. 1,582,347, April 27, 1926).

In the con-current roasting of sulfide ores, it has been observed that it is difficult to maintain ignition in the top of the furnace, when the fuel value of the ore is low, when feeding a large tonnage, or wet, or coarse material. To maintain the ignition, it is customary to use the hot air produced by cooling the central column and rabble arms of the furnace, but in certain instances this may not be sufficient.

The object of the present invention is to take heat, in the form of gas, away from the hottest zone of the furnace and transfer such heat to the incoming charge to evaporate moisture and ignite the ore.

The difficulty of maintaining ignition is overcome in this invention by introducing the air for oxidation at a point that is lower in the furnace than that at which the ore is introduced, preferably the second or third hearth, and allowing a portion of the air, and of the gases produced, to travel upward, and the rest to travel downward. That portion which travels upward is conducted by a series of flues, either in the walls of the furnace or externally to the furnace, as shown in the drawing, and is re-admitted to the furnace, at or below the point at which the air is admitted, or it may even be turned directly into the flues. A series of dampers in conjunction with a fan, or without a fan, where flue draft is sufficient, are employed to regulate the relative proportions of air and gases which travel upward and downward.

In that section of the furnace where the gases are travelling upward, only that portion of the sulfide sulfur will be eliminated which will be necessary to keep the charge ignited; the main desulfidizing reaction will

take place in that section of the furnace where the gases and solids are traveling concurrently.

By this process heat is taken from that section of the furnace which tends to become too hot, and is distributed to that section which is not hot enough. The heat throughout the furnace is balanced in a way to produce more rapid and more complete oxidation of the sulfur. Ores and concentrates, which otherwise would not furnish a self-sustaining roast, can by this process, be roasted efficiently without the use of extraneous fuel.

In the drawing, the process is disclosed as being carried out in a superposed hearth furnace; although other conventional types of furnace can, with suitable modifications, be used.

Referring to the drawing for a more complete disclosure of the invention:—

The figure is a vertical section of one type of furnace suitably modified to carry out the process.

The furnace is provided with a plurality of superposed hearths 2 and a hollow vertical rotary shaft 3, having secured thereto rabble arms 4. Alternate hearths are provided respectively with central openings 5 and peripheral openings 6, through which the ore drops as it travels from hearth to hearth.

The upper end of the hollow vertical shaft 3 is connected to a flue 7, which is provided with branches 8, 9, and 10 leading into the space above the second, third and fourth hearths and below the top hearth. The space above the top hearth is connected to a flue 11, which may be connected to a suction fan 12, the said flue 11 being provided with branch flues 13, 14, 15 and 16, leading into the spaces above the hearths which are below the first hearth.

Ore is fed in through a hopper 17 at the top of the furnace, the calcined ore being discharged through an opening 18 in the bottom of the furnace. Cold air may be admitted through the branch flue 19 and the products of combustion may be in part, or completely, led off to a stack through the branch flue 20. Valves 21 are suitably disposed throughout

the various flues for controlling the direction and amount of flow of the various gases.

Operation

5. Ore is fed into the upper part of the furnace through the feed hopper 17 onto the upper hearth. The roasting process will start by drying and igniting the sulfide ore on the first hearth. The ore will continue to roast 70 on the hearths below the first hearth, and will be discharged, usually at a high temperature, through the calcine discharge 18. Cold air fed into the bottom of the hollow column 3 will be substantially raised in temperature as 10 it enters the flue 7 on its way to the branch flues 8, 9, and 10. The air entering through the flue 8 below the top hearth will in a large part pass upward together with hot gases into contact with the ore on the top hearth, 15 providing thereby the necessary heat for drying the ore and effecting ignition. The heated air passing through the branch flues 9 and 10 will furnish the necessary oxygen for combustion on the third and fourth hearths and 20 25 lower hearths, the gases over these hearths travelling concurrently with the ore and being carried off through the flue 10a. It may be advisable to use one, two, or three flues for the introduction of air to the furnace 30 or any combination of flues 8, 9 and 10. In any combination for introducing air a portion of it will travel upward and the remainder downward.

The direction of flow of gases on the 35 hearths will be controlled in part by the fan 12. The fan is rotated so that the gases above the top hearth will be drawn into the flue 11, thus producing an upward current above the top hearths, whereas the fan will force the 40 gases through the branch flues 13, 14, 15 and 16, or any of these, thus causing a downward movement of gases over the ore on these hearths. The ore is stirred and moved from hearth to hearth in the customary manner 45 by the rotating rabble arms 4.

What we claim, is:

1. A roasting furnace provided with superposed hearths, an ore feed at the top of the furnace, and means for feeding air into the 50 furnace below the top hearth and above the bottom hearths, a portion of the air traveling upwards and the remainder downwards.

2. A roasting furnace provided with superposed hearths, an ore feed at the top of the 55 furnace, means for feeding hot gases upwardly onto the upper hearth and downwardly onto the lower hearths.

3. A roasting furnace provided with superposed hearths, an ore feed at the top of the 60 furnace, means for feeding air into the furnace below the top hearth and above the bottom hearths, a portion of the air traveling upwards and the remainder downwards, and means for exhausting gases from above the 65 top hearth.

4. A roasting furnace provided with superposed hearths, an ore feed at the top of the furnace, means for feeding air into the furnace below the top hearth and above the bottom hearths, a portion of the air traveling upwards and the remainder downwards, and means for exhausting gases from above the top hearth and feeding the said gases onto the bottom hearths. 70

5. A roasting furnace provided with superposed hearths, an ore feed at the top of the furnace, means for feeding hot gases upwardly onto the upper hearth and downwardly onto the lower hearths, means for exhausting the upwardly moving gases from above the 80 top hearth and for exhausting the downwardly moving gases at the bottom of the furnace

6. A roasting furnace provided with superposed hearths, an ore feed at the top of the furnace and a calcine discharge at the bottom of the furnace, means for continuously moving the ore through the furnace, means for feeding hot gases over the top hearth in a direction opposite to the direction in which the ore is moving, and means for feeding air for oxidation and hot gases over the lower hearths in the same direction as the ore is moving. 85

7. A roasting furnace provided with superposed hearths, an ore feed at the top of the furnace, means for feeding hot gases upwardly onto the upper hearth and downwardly onto the lower hearths, means for exhausting the upwardly moving gases from above the top hearth and for exhausting the downwardly moving gases at the bottom of the furnace, and means for feeding exhaust gases back onto the lower hearths. 90 95

8. A roasting furnace for sulphide ores provided with means for feeding ore at one end and discharging it at the other end, means for feeding air for oxidation intermediate the said ends, and means for moving hot gases over the ore at the feed end of the furnace to ignite the said ore. 100 11

9. A roasting furnace for sulphide ores provided with means for feeding ore at one end and discharging it at the other end, means for feeding air for oxidation intermediate the said ends, means for moving hot gases over the ore at the feed end of the furnace to ignite the said ore, and means for moving air, gases and ore in the same direction between the means for feeding air and the discharge end to desulphidize the said ore. 110 115

10. A roasting furnace comprising the combination with a plurality of communicating superposed hearths, of a hollow shaft passing through the hearths, means for admitting air into the shaft adjacent the bottom thereof, a conduit communicating with the shaft near the top thereof, the said conduit being provided with branches leading below the top hearth and above the bottom hearths, whereby air heated in the hotter regions of the fur- 120 125

nace may be supplied to the cooler portions of the furnace to facilitate the drying and roasting of material placed upon the cooler hearths, and means independent of the said conduit for withdrawing the products of combustion from the said hearths.

11. A roasting furnace comprising a plurality of superposed hearths, a hollow shaft passing through the said hearths, means for admitting air into the shaft adjacent the bottom thereof, a branched conduit connecting the upper portion of the said shaft with a selected plurality of hearths, whereby the air passing through the shaft becomes heated in the hotter portions of the furnace and is discharged into the cooler portions thereof, the heat of the said air being utilized to facilitate combustion in the cooler portions of the furnace, and means for exhausting the products of combustion from the top and bottom portions of the furnace, whereby a portion of the admitted air and of the furnace gases travels upwards and the remainder downwards.

12. In a roasting furnace comprising superimposed hearths having passages and means for moving the ore downward from hearth to hearth, means for producing a current of air counter to the direction of the ore movement through the upper portion of the furnace, for creating a zone of maximum air pressure in an intermediate portion of the furnace, and for producing a current of air in the direction of ore movement in the lower portion of the furnace.

13. In a roasting furnace comprising superimposed hearths having passages and means for moving ore from hearth to hearth from the top hearth down through the lower hearth, an air outlet at the top hearth, an air outlet at the lower hearth, and an air inlet at an intermediate hearth having connection through the respective hearths with said top and bottom outlets.

14. In a roasting furnace comprising superimposed hearths having passages and means for moving ore from hearth to hearth from the top hearth down through the lower hearth, an air outlet at the top hearth, an air outlet at the bottom hearth, and an air inlet opening into two consecutive intermediate hearths.

15. In a roasting furnace comprising superimposed hearths having passages and means for moving ore from hearth to hearth from the top hearth down through the lower hearth, an air outlet at the top hearth, an air outlet at the bottom hearth, and an air inlet opening into two consecutive intermediate hearths, and means for causing such air movements in opposite directions in the furnace.

In testimony whereof, we affix our signatures.
